UNITED STATES PATENT OFFICE.

FREDERICK HENRY PERRY, OF BEVERLY, MASSACHUSETTS, ASSIGNOR TO UNITED SHOE MACHINERY COMPANY, OF PATERSON, NEW JERSEY, A CORPORATION OF NEW JERSEY.

PATTERN-GENERATING APPARATUS.

1,027,562.

Specification of Letters Patent.

Patented May 28, 1912.

Application filed February 12, 1908. Serial No. 415,567.

To all whom it may concern:

Be it known that I, FREDERICK H. PERRY, a citizen of the United States, residing at Beverly, in the county of Essex and Commonwealth of Massachusetts, have invented 5 certain Improvements in Pattern-Generating Apparatus, of which the following description, in connection with the accompanying drawings, is a specification, like reference characters on the drawings indicating 10 like parts in the several figures.

This invention relates to mechanism for generating patterns, and is of especial utility when employed in the production of patterns 15 for sole rounding machines for use in the manufacture of boots and shoes, although I contemplate the use of my invention in any field to which it is adapted by the nature of my improvements.

20 My device may be used to notable advantage in conjunction with a model or a sample shoe, constituting the primary pattern, to reproduce upon the periphery of a pattern blank or disk the niceties of contour which are formed by variations in the width 25 of the sole edge, *i. e.*, that portion of the sole which projects and is visible beyond the upper of the shoe. The pattern thus produced may then be employed in a machine 30 of suitable construction for trimming or rounding soles previously attached to the uppers, preferably one of a type which I have invented for the special purpose, and which is disclosed in my co-pending applications 35 for U. S. Letters Patent, Serial No. 559,332 filed May 4, 1910, and Serial No. 679,765 renewed February 24, 1912, a type of machine in which mechanism controlled by the pattern acts to trim the soles of any 40 desired number of shoes operated upon, to form on their edges a counterpart of the model or of the peripheral contour of the sole edge of the sample shoe. In most shoes the edge of the sole is of varying width and 45 the contour of the sole is an important factor in its appearance, it being of course particularly important that the soles of both shoes of a pair should be of similar contour. Prior to my invention of the sole 50 rounding machine employing these patterns, it has been a frequent practice to rely upon the eye of the operator of the sole rounding machine, which is used to round soles al-

ready attached, to secure the proper contour for the sole edge of a shoe having a sole edge 55 of varying width by imitation of a sample sole edge and this has been one of the most difficult and responsible operations in the manufacture of shoes.

Variations from the sample have been 60 usual; often the discrepancy has so marred the style as to diminish the value of the product; occasionally mated shoes have varied from each other so seriously that one or both has required alteration, with resultant 65 expensive loss of work, and not infrequently one or both of the pair is discarded with complete or partial loss of material.

To eliminate the personal factor is an important object of my invention, and as 70 the varying projection of the sole edge furnishes the characteristic to be reproduced, I provide according to the preferred embodiment of my invention pattern or model-copying mechanism, including a guide or abutment preferably rotary, to be engaged and traversed by the sole edge or other suitable model, and preferably actuated positively to feed the model at a speed having a constant ratio to the speed or rotation of the 80 disk to be patterned, until the entire length of the model surface has traversed the feeder; and concurrently with this traverse of the sole edge, a follower member, also forming part of the copying mechanism, is 85 maintained in contact with the traveling surface of the shoe upper adjacent the region of the sole edge contacting with the abutment or rotary feeder; the follower projecting over the edge of the sole and beyond 90 the edge of the abutment to an extent varying with the changing width of those portions of the sole edge traversed, and corresponding closely with the variations in contour of the sole, however frequent or abrupt. 95 Coöoperating with this follower is a pattern generating device of any suitable construction, which may conveniently take the form of a rotary cutter, when a disk or similar blank is to be cut peripherally to pattern, 100 and this device is suitably connected with the follower to provide for control of the generator by the follower, this result being attained satisfactorily by mounting the cutter rotatively in bearings upon a movable 105 support which carries the follower and

swings therewith as a unitary relatively rigid structure about a pivot, to maintain the follower in operative contact with the primary pattern and to maintain the cutter 5 in corresponding varying operative contact with the blank disk to be cut to pattern. The disk after having been thus patterned corresponds detail for detail with the sole edge or other model or primary pattern, and 10 is ready for use in the sole rounding machine. It may be used also as a master pattern in the production of similar disks either by causing it to traverse the rotary abutment while another pattern disk is engaged oper- 15 atively by the rotary cutter, or by arranging the master pattern disk coaxially with respect to the blank or disk to be cut to pattern, rotating them in unison, and arranging coaxially with the rotary cutter a fol- 20 lower disk or device which will engage the periphery of the master pattern disk and regulate the depth of cutting effected by the cutter, according to the varying radii of the rotating master pattern disk.

25 Another important object of my invention is to provide means to mark the pattern at points easily visible to the operator of the sole-rounding or other machine in which the pattern is to be used, so that the operator 30 in setting the stops which control the operation of the rounding mechanism preparatory to use of the pattern can readily see by the mark upon the toe-shaping portion of the cam, where to set the stop which controls the 35 operation of the rounder upon the toe of the shoe; and other salient features of the sole edge will be observed in marking the pattern, so that if the operator follows these indicia faithfully he can set the stops on his 40 rounding machine with accuracy, insuring the rounding of the sole edges to correspond closely with that of the sample shoe.

Means to throw the rotary cutter out of operative position at will, and means to 45 maintain it out of operative position, independently of the actuating mechanism, are also provided; and I have included also means to hold the cutter at a point of operation where it will shape automatically the 50 inactive "limb" of the pattern, which term I will use hereinafter for the sake of brevity to designate that portion of the periphery of the pattern which is usually inoperative in the sole-rounding or other machine in which 55 the pattern is used eventually. This limb will preferably be of uniform radius.

My invention contemplates also the simultaneous production of a plurality of patterns by the use of a cutter or other generator 60 which will engage and shape at the same time a number of disks arranged coaxially. To facilitate this I have devised connectors applicable to adjacent disks and serving to 65 couple them together for co-rotation with each other and with their actuating shaft.

Other objects of my invention comprise means preferably formed in connection with the pattern actuating shaft or other work support to enable the operator to locate each blank in proper position so that the generator will start work at a similar predetermined region of each blank; also means for regulating the feeding mechanism of the model and the blank independently of the generator, where the generator, model-feed 70 and blank are driven from a common source of power.

The invention will be more fully explained in the following description, reference being had to the accompanying drawings, in which is shown one form of apparatus by the aid of which the invention may be practised.

Figure 1 is a view in perspective of the complete machine, with dotted lines indicating a model or sample sole in operative position to serve as a primary pattern; Fig. 2 shows the operating parts in plan view, with the casing broken away except at the point of support for the generator-regulating dogs; Fig. 3 is a vertical, sectional view on the line x^3-x^3 Fig. 2, looking from right to left, and showing the model shoe, the rotating model feeding abutment and the follower member in operative position; Fig. 4 is a similar detail view on the line x^4-x^4 , Fig. 2, showing the rotating cutter or generator, and the pattern blank actuating shaft and fittings, with a pattern blank disk mounted in operative position thereon; Fig. 5 is a fragmentary detail view in perspective of a plurality of coaxially arranged pattern blank disks with their actuating hub and connectors; Fig. 6 is a detail view in front elevation of the disengaging means for 95 the swing arm; Fig. 7 is a plan view illustrating separately and on an enlarged scale, the clutch for controlling the operation of the model and pattern feed, parts being broken away to reveal the inner connections 100 between the loose worm and the counter shaft, to be described hereinafter; Fig. 8 is a fragmentary detail view in vertical section taken on the broken line x^8-x^8 , Fig. 2, looking from left to right, showing the actuating 105 mechanism for the marking device, the marker itself being shown in elevation, with its shaft broken away and shortened to bring it within the limits of the drawing; and Fig. 9 is a fragmentary vertical sectional view 110 taken on the line x^9-x^9 , Fig. 1, showing the main actuating pulley, its bearing and adjacent parts. Fig. 10 is a view from the 115 front of the machine with the casing broken away; and Fig. 11 is a view in rear elevation of the machine to show the arrangement of levers, etc.

The machine herein shown for practising my invention comprises a generator 1 of any suitable construction, taking in the instance 120

illustrated the form of a rotary cutter mounted upon, and actuated by, a vertical shaft 2 carried in bearings 3 near the end of a swinging arm 4 mounted securely, as by shrinking or otherwise, upon a vertical shaft 5, the latter being removably and rotatably mounted in a hollow bearing bushing 6, (see Fig. 9) carried by the casing 7, which may rest on a table or other suitable support and be secured thereto by fastening means passing through the lugs 8.

The hollow bushing 6 may serve as the bearing for the main actuating pulley 12 of the machine, actuated by any suitable means, one convenient form of such actuating means being illustrated at 9 which designates a belt running around idle direction pulleys 10 and 11, (from a suitable source of power not shown) to the lower groove of the pulley 12 loose on the vertical bushing 6, the upper groove of this pulley serving to receive a belt 13 running to a pulley 14 on and driving the vertical generator shaft 2 and its attached rotary cutter 1, whatever the angular position of the swing arm 4. 15 is a take-up pulley for the belt 13, (see Fig. 2).

The disk or blank 16 to be cut to pattern or otherwise shaped, (see Fig. 2) is mounted in the same horizontal plane with the generator 1, which cuts into the periphery of the blank to a degree depending on the distance between the axes of the cutter and blank, this being determined by the angular position of the swing arm 4 relatively to the longitudinal axis of the machine. This angular positioning of the generator arm may be regulated by any convenient and suitable means, manual or mechanical, and 40 in Figs. 1 and 2 I have shown a follower and regulating device 17 of a character especially useful in copying the sole 18 of a shoe 19 whose upper 20 is presented by the operator for running engagement with the nose of the follower. A spring dog or plunger 21 mounted at 22 in the casing 6 presses against the heel 23 of the swing arm, normally forcing the generator and follower leftward to engage the disk 16 and 45 shoe upper 20 respectively. In the instance illustrated, the follower 17 is mounted, (pivotally preferably, to permit smooth traversal by the shoe) near the free end of an arm 24 connected with the swing arm 4, and which may be formed integrally or as 50 a unitary structure with the latter and swinging therewith over the sole edge portion 25 as the operator moves the same along past a guide or abutment 26.

55 The sole edge narrows toward the tip in the instance illustrated, and as the operator passes the shoe along toward the left, from the position shown in Fig. 2, until the point 27 is reached, maintaining the edge 60 25 of the sole in engagement with the abut-

ment 26, the upper 20 crowds the follower 17 over toward the abutment 26, and the arm 24 turns the arm 4 with the shaft 5 and swings the generator 1 outward radially from the pattern blank 16 so that the cutter 70 does not enter so deeply into engagement with the periphery of the disk 16, which is rotated by suitable means to be described later, and the line of the cut follows approximately that of the elongated dots 28 75 seen within the periphery of the pattern blank disk in Fig. 2. This peripheral cut should correspond closely in detail with the contour of the sole edge 18—27 and thence along the opposite side of the sample shoe, 80 and in order to insure the movement of the sample at a speed bearing a fixed ratio to that of the disk which is being cut to pattern, whether the speed be higher or lower, I prefer to construct the abutment 26 as a 85 horizontally disposed counter shaft 31 mounted rotatively in bearings 32, (see Fig. 1) on the base of the machine and driven by a spiral gear 33 meshing with a worm 34 on the hub of the pulley 12, the counter shaft 90 31 carrying a sleeve member 35 provided with a driving worm 36 which meshes with a gear 37 on the vertical shaft 38 (see Fig. 4), and through it and the clutch 71 drives the pattern blank disk 16.

95 The rotary abutment or feed wheel 26 (see Fig. 3) receives its actuation through a vertical shaft 39 mounted in a frame pillar 40 and carrying a relatively small gear 41 which meshes with a larger intermediate gear 42 mounted on a stud or bolt 43, and actuated in turn by a gear 44 fast on the vertical shaft 38. The gears 42 and 44 are preferably considerably larger than the gear 41, to cause faster rotation of the 100 rotary abutment or feeder 26 than of the disk 16, and the abutment preferably has peripheral teeth or roughnesses to engage and feed positively the sole-edge pressed thereagainst, and may have a guide flange 105 45 to position the sole properly with relation to the feed wheel; and also to position the upper 20 with relation to the follower 110 17, as seen best in Fig. 3.

115 In order to permit stoppage of the rotation of the pattern blank disk at any desired point regardless of the continued rotation of the main actuating pulley 12 and the generator 1, I prefer to interpose a clutch device between the counter shaft 31 120 and the feed devices, and as one convenient form of such a clutch device (see Fig. 7) I have formed the worm 36 upon a sleeve 35 mounted loosely on the counter shaft 31 between collars 46, 47 fastened to the shaft by 125 130

- pins 48, this worm sleeve constituting one member of the clutch, and preferably being provided with a split brake block consisting of two halves 49, 50 embracing the sleeve 35 and secured in adjusted position by a screw 51. This brake serves to stop the worm sleeve promptly upon disengagement of the clutch, so that the pattern blank disk will not be fed improperly. The other 10 member of the clutch (see Fig. 7) consists of a cap 52 having a head portion 53 provided with a pin 54 traversing a slot 55 in the shaft 31 and serving to communicate the motion of the shaft 31 to the cap, which 15 in turn operates the worm sleeve through the medium of a pin 56 and socket 57 connection. The cap 53 can be grasped manually and drawn outward axially toward the left to disengage the sockets from the 20 pins, when the action of the brake 49, 50 will stop the rotation of the worm sleeve 35; but the cap cannot be withdrawn completely from the shaft without removal of the pin 54.
- 25 Preferably the disengagement of the clutch members will be effected before withdrawal of the sample shoe from engagement with the abutment 26 and the follower 17, in order to avoid the undue cutting away 30 of the periphery of the pattern, which would result normally under the action of the cutter 1 pressed thereagainst by the spring plunger 21.
- 35 The swing arm 4 may be moved outward against the action of the plunger 21 to swing the cutter away from the disk by any suitable means, and as one convenient form of such means I have shown (see Fig. 6) a bell crank lever 58 mounted pivotally at 59 upon the base of the machine, one arm 60 of the lever extending upward into position to engage a coöperating depending arm 61 integral with the swing arm, while the other arm 62 of the bell crank extends outward 45 beyond the frame of the machine and is provided with a connecting rod 63 extending downward to a treadle or other suitable operating device, (see Fig. 1). After the swing arm has been moved outwardly by 50 this means, I prefer to utilize suitable means to hold it positively at its outer position of disengagement. One suitable device for this purpose is illustrated at 64 which designates a dog mounted pivotally upon a rod 65 carried in lugs 66 upon the top of the machine base. Normally this dog will be left in the upright position shown in Fig. 1, where it does not interfere with free swinging of the arm 4 toward the pattern blank 60 disk, but when the dog 64 is moved down into a horizontal position by the operator, the dog will be engaged by the portion 67 of the arm 4 and the arm will be held outward away from the disk. A similar dog 68 may 65 be provided, of such a length that when it

is lowered into horizontal position it will stop the arm 4 in such a position that the cutter 1 will engage the periphery of the disk 16 only slightly and will cut automatically to a given radius the limb of the disk, *i. e.* that portion of the periphery which will be inactive in the sole rounding or other machine in which it is used eventually.

70 Among the important objects of my invention, one of the most notable is the provision of means to enable ready application of the pattern blank disks to the vertical actuating shaft 38, and their easy removal therefrom. The means which I prefer to 75 use for this purpose may be seen best by reference to Fig. 4, in which the reference numeral 30 designates a post member having a threaded shank 69, entering a threaded axial recess 70 in the upper end of the shaft 80 38, the latter having a driving clutch member 85 consisting of a collar or flange 71 secured to the shaft by a pin 72, preferably at a shoulder 73 provided to support the driving member; or the flange 71 may be integral with the shaft 38.

90 The collar 71 is shown as having a beveled periphery 74 to receive a coöperating friction clutch member 75 and drive it frictionally to actuate the disks to be cut to pattern, 95 and this driven member may be connected operatively with the disks by any suitable means. As one convenient form of such means, I have shown a spline 76 arranged vertically within notches, one in the periphery of the clutch member 75 designated by the reference numeral 77 and another in the periphery of the hub device 78, this notch being designated by the reference numeral 79, the spline being held by a 100 peg or post 80 inserted in a socket in one of the members, preferably the hub, in such a position that the spline extends vertically across from the clutch to the hub and also into a slot 81 in the disk 16, thus coupling 105 the clutch, hub and disk together. When the shaft 38 is rotated and with it the flange 71, the clutch member 75 is rotated also by frictional engagement with the flange, and in its turn rotates the hub 78 through the 110 medium of the spline 76, and at the same time rotates the pattern blank disk 16 carried by the hub, the disk having an axial aperture 82 to receive the boss 83 on the lower side of the hub. By making the post 115 member 30 of the shaft sufficiently long, room can be provided to receive a plurality of disks as 16, 85; at the same time, as shown in Figs. 4 and 5, each having preferably a hub as 78, 86 and a spline 76, 87.

120 Suitable means should be provided to retain the pattern blank disks in adjusted position and as one convenient form of such means, I have shown the post 30 as having a washer or washers 88 to overlie the adj- 125 130

cent hub, this washer being preferably detachable and provided with an open slot 89 (see Fig. 1) which permits the washer to embrace the threaded end 69 or a reduced portion 90 of the post, while the thumb-screw wings 91 are secured pivotally by a pin 92 in a slot 93 in the upper end of the shank of the thumb-screw, so that they can be turned upwardly into the position indicated in dotted lines in Fig. 4, so that after the washer 88 has been withdrawn the hub 83 can be raised readily and removed over the head of the thumb-screw and an uncut pattern blank disk substituted for engagement by the cutter.

After one disk has been cut to pattern, in the manner already described in connection with the use of a sample shoe as the primary pattern, I contemplate the super-position thereon of another pattern blank disk, as shown at 85 in Fig. 4, and the sample shoe may then be omitted, the disk 16 already cut to pattern serving as a secondary or master pattern in co-operation with a follower roll or disk 94 (see Fig. 1) mounted co-axially with the generator 1 upon the vertical shaft 2 which actuates the rotary cutter, this follower disk being shown in Fig. 1, beneath the cutter and in engagement with the master pattern disk 16, beneath the pattern blank disk 85 which is in the same plane with the cutter. The washer 88 seen in Fig. 1 is the uppermost of those shown in Fig. 4. The lower position shown in Fig. 4 is occupied by it when a single pattern is being shaped. Two pattern blank disks may be cut to pattern at once by using a sufficiently long cutter as indicated by dotted lines in Fig. 4.

It is important that the cutting operation should begin always at a predetermined point, and to regulate this automatically any suitable means may be provided. I have shown for this purpose a swing arm 95 mounted pivotally above the top of the casing at 96 upon a bolt 43, which serves also in the instance illustrated as the vertical bearing for the intermediate gear 42. The arm has preferably a beveled tip at its free end which can be held manually against the pattern blank disk support 75 until the latter brings a notch 97 opposite the tip 98 and the tip enters the notch. When the machine is ready for operation the tip may be withdrawn readily by swinging the dog outward, or it will clear itself from the notch when the machine is started.

Another important object of my invention is to provide means to mark upon the disk suitable index points which can be readily observed by the operator who uses the disk upon a sole rounding or other suitable machine, so that the operator can readily determine how to set the stops in that machine so as to control properly ro-

tation of the pattern disk, it being understood that in a sole rounding machine the rounding devices operate upon the edge of the sole to an extent corresponding exactly with the radius of the pattern at any given point. For example, referring to Fig. 2, the dot designated by the reference numeral 99, serves as a mark to indicate to the operator of the rounding machine that a certain stop is to be arranged for stoppage of the pattern disk, inasmuch as that portion of the periphery of the pattern disk adjacent the dot serves to control the rounding of the tip, the pattern having itself been cut away in correspondence with the relatively narrow portion of the sole edge of the sample shoe at the region designated by the reference numeral 27, in Fig. 2.

As a convenient form of pattern marking device, I have shown (see Figs. 2 and 8) a point 100 carried near the free end of the spring shank 101 of a hammer device 102 pivoted, as at 103, in a suitable housing or support 104 secured in the instance illustrated upon the top of the arm 4 by screws 105. The hammer has an upwardly projecting portion 106 against which bears a plunger 107 contained in a recess 108 and actuated by a spring 109 seated against a retaining nut 110. A set screw 111 bearing 95 against the forward side of the portion 106 holds the same in position to maintain the point 100 sufficiently clear from the face of the disk 16 to permit free rotation of the latter, but in such close proximity that the 100 resiliency of the shank 101 will permit the point to engage the face under the influence of the hammer, as will now be described. Upon the heel 112 of the hammer, I have shown a pivoted latch 113 engaged by a 105 spring 114 normally pressing the latch outward into engagement with the periphery of a rock shaft or trigger 115 mounted in a horizontal bearing in which it can be rotated by a crank 116 (see Figs. 1 and 2) 110 having a connecting rod 117 running down to a treadle or other suitable operating device 118. The rock shaft 115 has a notch 119 the wall of which catches the latch when the operator rotates the rock shaft by depressing the treadle, and upon further rotation of the rock shaft, the latch is crowded out of the notch, releases the heel of the hammer and the latter is forced downward by the action of the spring 109, which results in a sharp, staccato blow of the point 100, causing a slight but perceptible indentation of the disk 16, as at the point designated by the reference numeral 99 in Fig. 2. The rock shaft trigger 115 is returned 125 to normal position by a spring 120 acting upon release of the connecting rod 117.

The general operation of the machine is as follows:—The wings 91 of the thumb screw post having been raised into the posi-

tion illustrated in dotted lines in Fig. 4, the disk or pattern blank 16 with its hub 78 is placed over the upraised wings and dropped down into position over the clutch member 75, with the spline or connector 76 extending from the notch 79 of the hub into the notch 77 of the clutch member. The washer 88 is then applied horizontally with its notch 89 upon the threaded portion 69 of the thumb screw post, the wings of the latter are turned downward and the thumb screw tightened to hold the hub and disk snugly in place upon the clutch, which is crowded against the flange 74. If the cutter 1 is not already rotating, the belt 9 may now be set in motion, and after the portion 18 of the shoe sole has been placed in contact with the abutment 26 as illustrated in Figs. 1 and 2, the dog 64 is raised to permit the plunger 21 to swing the arm 4 around to bring the generator 1 into operative cutting engagement with the periphery of the disk 16, this being the position shown in Fig. 2, where the cutter has entered deeply into the disk and shaped the disk at that point in correspondence with the relatively wide edge of the sole at the portion 18. This deep cut is permitted by the relatively large displacement of the follower 17 which has swung over into engagement with the upper at 20. The operator then presses in the clutch cap 53, the tip of the arm 95 is cleared from the notch 97 and the rotation of the counter shaft 31 is transmitted through the worm 36 to the gear 37, shaft 38 and thereby to the gears 44, 42 and 41, and the shaft 39. The abutment 26 is thus rotated to feed the sole edge 18-25-27 along from right to left, the narrowing width permitting the upper to crowd back the follower 17, and at the same time the pattern blank disk 16 is rotated by the shaft 38 in the direction of the arrow, at a much lower speed, in the instance illustrated, but at a proportionately constant ratio, so that the narrowing peripheral cut indicated by the broad dots in Fig. 2 corresponds exactly in contour with the varying width of the sole edge. The operator should maintain the sole edge in true tangency with the rotary abutment at a point lying in a line passing from the axis of the rotary abutment through the mid-point 121 of the follower 17, and to assist the operator in accomplishing this I have shown a mark on the follower at the mid-point 121 and a corresponding mark 122 on the adjacent arm 24, these marks, when aligned, indicating that the sole is properly positioned. After the portion 18-25-27 has traversed the follower, the opposite side of the sole edge is caused to traverse in like fashion, from the point 27 to the point 29 &c. causing the pattern to be shaped, and then the dog 68 is dropped, the arm 4 allowed to rest thereagainst, and the

limb of the pattern is shaped automatically to a circle of predetermined radius. This completes the operation and the operator will then depress the rod 63, throwing out the arm 4 and cutter 1; will drop the dog 64 to hold the cutter away from the pattern; and will replace the pattern by a new blank disk, first loosening slightly the thumb screw, raising its wings 91, sliding out the washer 88 and withdrawing the disk 16. As already indicated, the pattern 16 may alternatively be left in place to serve as a master pattern, in which event a fresh pattern blank disk 85 (see Fig. 4) provided with a hub 86 and spline 87 will be imposed upon the hub 78, and the upper washer 88 will be placed in the upper groove 90 of the stud 30, presenting the appearance shown in Fig. 1. The retaining nut 123 and the cutter 1 will be removed from the generator actuating shaft 2, a follower disk or roll 94 will be applied to the shaft 2 and the cutter and retaining nut will be replaced, after which the swing arm 4 may be released and the clutch 53 coupled. The follower roll or disk 94 will be forced, by the action of the plunger 21, into engagement with the periphery of the master pattern 16 at all points, accompanied by similar cutting engagement of the generator 1 with the pattern blank disk 85, which will thus be shaped as an exact replica of the master pattern 16, and further replicas may be produced automatically without further attention to the machine than is involved in removing each replica as it is finished and substituting a fresh pattern blank disk.

While, in the use of a machine embodying this invention for producing a pattern or a cam to be used in the manufacture of shoes, it may be more convenient to employ a sample shoe as a model in the manner hereinbefore described, it should, nevertheless, be understood that the invention is not limited to the use of a shoe as a model; although it is essential that such model as is employed shall have a shape corresponding in certain desired characteristics with the article in the manufacture of which the pattern is ultimately to be used.

Having described my invention, what I claim as new and desire to secure by Letters Patent of the United States is:—

1. In a machine of the class described, a support for a pattern blank, means for operating upon said pattern blank, a gage and a follower arranged for movable engagement respectively with the same side of the model at regions thereof differing in contour and in substantially the same plane transversely of the direction of relative movement therebetween, and connecting mechanism whereby relative movement of said pattern blank and said operating means in correspondence with the relative varia-

tions in contour of said engaged model regions, is effected by relative movement of said gage and said follower.

2. In a machine of the class described, a support for a pattern blank, means to operate upon said blank, means arranged and adapted to movably engage in parallel lines with diversely irregular portions of a model, such as the upper and the sole edge of a shoe, and connecting mechanism between said model engaging means and said operating means to permit the latter to produce on said blank a pattern surface embodying the relative variations between the model portions engaged respectively.

3. In a machine of the class described, a support for a pattern blank, means for operating upon said pattern blank, a feeding device for engaging the sole of a model shoe, a follower for engaging the upper of said model shoe, and connecting mechanism whereby relative movement of said pattern blank and said operating means is effected by relative movement of said feeding means and said follower.

4. In a machine of the class described, a support for a pattern blank, means for operating upon said blank, a gage having movable engagement with a portion of a model differing in shape from said pattern blank, a follower having movable engagement in a parallel plane with another and diversely shaped portion of said model, and means connecting said follower and said operating means for positioning said operating means to produce a pattern surface on said blank having a predetermined relation to the variation between the model portions engaged respectively by said gage and follower.

40 5. In a machine of the class described, mechanism for producing in a pattern of dissimilar general shape from the model, variations of contour capable of serving as pattern surfaces in the reproduction of shapes similar to said model; said mechanism comprising means arranged and adapted for movable engagement with said model at a plurality of regions of said model differing in contour and having predetermined positions respectively relatively to the direction of relative movement between said model and model-engaging means; a pattern-blank support; means to operate upon said blank; and connecting means between said model-engaging means and said operating means to permit the latter to produce upon said blank a pattern surface embodying the relative variations between the model portions respectively engaged.

60 6. Pattern copying mechanism for machines of the class described; comprising a swing lever having a substantially straight shank provided near one end with a pivot bearing and near its other end with a pattern cutter, and having a medial, lateral

arm provided with a model follower, said lever being adapted to swing in a substantially horizontal plane with said cutter and follower in view of the operator.

7. Pattern copying mechanism for machines of the class described, comprising a swing lever provided near one end with means to permit pivotal support of said lever and having near its other end a shaft provided with a rotary pattern generating cutter, said lever having also a medial laterally extending follower arm provided with a swiveling model follower, and means to support said lever to swing with said cutter and follower in a substantially horizontal plane around said pivotal support and in uninterrupted view of the operator.

8. A pattern copying device for machines of the class described provided with a model follower and a pattern generator, and having manually operated controlling means, and means tending to swing said follower and generator normally toward the primary pattern and the article to be patterned respectively; said device comprising a lever adapted to act in a substantially horizontal plane, and provided with an intermediate pivot bearing, one longitudinal arm of said lever being elongated and provided near its free end with a bearing for said pattern generator, and provided with oppositely extending lateral arms, one arranged to receive said model follower, and the opposite arm being arranged to be engaged by said manually operated controlling means; and the other longitudinal arm of said lever beyond said bearing being arranged for engagement by said swinging means.

9. In a machine of the class described, a base, a lever mounted pivotally thereon and provided with a pattern generator, said lever having a downwardly extending projection; a bell-crank lever mounted on said base and having one arm arranged to engage said projection loosely; and a treadle to operate said bell-crank, to permit the operator to alter manually the operative position of said pattern generator; and means to maintain said generator in predetermined position regardless of the position of said treadle, but permitting operation of the latter.

10. In a machine of the class described, a rotary support for a pattern blank, means for cutting said blank, a gage and a follower arranged and adapted respectively to movably engage in parallel planes diverse portions of a model, means connecting said follower and said cutting means for imparting movement from the follower to the cutting means, means for operating said cutting means and adjustable means for holding said cutting means in engagement with said blank.

11. In a machine of the class described, a

5 rotary support for a pattern blank, means for cutting said blank, a gage and a follower arranged and adapted respectively to movably engage in parallel planes diverse portions of a model, means connecting said follower and said cutting means for imparting movement from the follower to the cutting means, means for operating said cutting means and adjustable means for holding said 10 cutting means in engagement with said blank.

12. In a machine of the class described, a rotary support for a pattern blank, means for cutting said blank, a gage and a follower 15 arranged and adapted respectively to movably engage in parallel planes diverse portions of a model, means connecting said follower and said cutting means for imparting movement from the follower to the cutting 20 means, means for operating said cutting means and means for holding said cutting means and follower in disengagement with the blank and model respectively.

13. In a machine of the class described, a 25 rotary support for a pattern blank, means for cutting said blank, a gage and a follower arranged and adapted respectively to movably engage in parallel planes diverse portions of a model, means connecting said follower and said cutting means for imparting movement from the follower to the cutting means, means for operating said cutting means and means for holding said cutting means at a fixed distance from the axis of 30 rotation of the blank supporting means.

14. In a machine of the class described, a rotary support for a pattern blank, means for cutting said blank, a gage for engaging a portion of a model, a follower for engaging 40 another portion of the model, means connecting said follower and said cutting means for imparting movement from the follower to the cutting means, means for operating said cutting means and means connected removably with said blank for engaging said support, to hold said blank positively in place thereon, said holding means being removable freely with said blank from 45 said support, and a key removable freely from said blank when said blank has been removed from said support, and said key being itself locked in place when said blank is in position upon said support.

15. In a machine of the class described, a 55 pattern generator; a pattern blank support; a movable primary pattern feeder; all arranged to operate in parallel horizontal planes in unobstructed view of the operator; and means to actuate said generator, support and feeder respectively, said means comprising a vertical shaft forming part of said pattern blank support, similar vertical shafts for said generator and feeder respectively, and an actuating member connected with 60 said shafts respectively by operating devices

arranged below the level of said generator, support and feeder respectively.

16. In a machine of the class described, a hollow bearing bushing provided with a loose actuating pulley and a gear rotatable with and by said pulley; a pattern blank shaft also provided with a gear; a bearing stud rotatable within said bearing bushing; a lever rotatable with said bearing stud as an axis and provided at its free end with a 70 shaft carrying a pattern generator and a pulley; a counter shaft connecting said gears operatively; a belt connecting said pulleys operatively; and means to operate said actuating pulley to drive said generator and pattern blank shaft respectively; said pattern blank, pattern generator and lever being arranged in substantially parallel planes above said countershaft, pulley and other operating instrumentalities, to afford 75 unobstructed vision thereof by the operator.

17. In a machine of the class described; a base; a main actuating member mounted rotatively on a vertical bearing on said base and having a pulley and a gear rotatable therewith; a shaft provided with gears and a pattern blank support, and a shaft provided with a feeder, to engage the primary pattern, said shafts being mounted rotatably in vertical bearings on said base and connected by gears to cause co-rotation of 80 said feeder with said support; a countershaft having near one end a gear intermeshing with said gear rotatable with said actuating member and provided with a manually operated clutch member, and a co-operating clutch member having a gear intermeshing with one of said gears on said pattern blank shaft to permit rotation thereof by said actuating member, subject to control 85 by said clutch; a lever mounted to swing horizontally about said vertical journal and provided near its free end with bearings, and a shaft in said bearings carrying a generator and a pulley, said lever having an 90 arm provided with a follower maintained by said arm in position above said feeder to engage said primary pattern; means to maintain said follower in following relation with said primary pattern, and to maintain said generator in correspondingly varying operative relation with said pattern blank; means to operate said actuating 95 member; a belt connecting said pulleys to drive said generator; and means to control 100 the swinging of said lever independently of said primary pattern.

18. In a machine of the class described; an actuating member; a rotatable pattern-blank support and a manually controlled 105 stop therefor; a counter shaft to permit rotation of said pattern blank support by said actuating member; and a clutch interposed between said counter shaft and support, said clutch comprising a sleeve loose 110

on said counter shaft and connected operatively with said support, a sliding clutch member connected relatively with said counter shaft, and operating connections 5 between said sleeve and sliding member, said sliding member having a manually operable portion adjacent to said stop, and a choking brake upon said sleeve to stop rotation of said pattern-blank upon disengagement of said clutch.

19. In a machine of the class described; a rotatable support for a pattern blank; a pattern generator and its support movable laterally with respect to said rotatable support; means movable with said generator support into a position over said pattern blank to mark the face thereof, and withdrawable from over said pattern blank; and means to actuate said marking device.

20. The combination with a pattern generator and its support, of marking mechanism; comprising a marker, a spring operated hammer to actuate said marker, a manually operated trigger; and mechanism 25 to actuate said trigger and thereby to cause said marker to deliver a staccato marking blow into engagement with said pattern, retiring instantly from said engagement.

21. In a machine of the class described, 30 a movable support for a pattern blank; means for operating upon the pattern blank; a follower arranged for engagement with the model, and a punch to mark points upon said blank, said operating means, follower and punch being connected to move together as a unitary structure; and means for actuating the same.

22. Mechanism of the class described comprising a pattern-blank-support, and 40 means to rotate said pattern-blank; a swing arm provided with a pattern-generating cutter adapted to be engaged with said rotating pattern-blank, said swing arm having also a hammer-operated spring marking point; and a treadle to actuate said hammer.

23. In a machine of the class described, 50 a rotatable support for a pattern blank disk, means for operating upon said disk, a gage and a follower arranged respectively for movable engagement in parallel horizontal planes with diverse portions of a model eccentric to said gage, connecting mechanism whereby relative movement of the pattern blank and said operating means is effected by relative movement of the gage and follower, means for actuating said supporting means, and a friction clutch for engaging said supporting means with said 55 actuating means, said clutch and support being arranged to rotate in horizontal planes parallel with, and closely adjacent to, the plane of said gage.

24. In a machine of the class described, a 60 loose clutch member constituting a support

for a pattern blank disk, and having a recess; a coöperating clutch member to actuate said support, and a yielding arm to enter said recess to locate points in the movement of the same and to be itself automatically dislodged from said recess by the movement of said support; said loose clutch member being normally rotatable manually apart from said coöperating clutch member; and means to couple said clutch members.

25. In a machine of the class described; an upright post to support rotatively for generation a plurality of co-axially arranged pattern disks provided with central 70 apertures to pass said post, the latter having its upper end presented in position to receive said disks freely, one of said disks constituting a master pattern; means to hold said disks on, and rotatable with, said post; and means to operate upon said disks simultaneously, said operating means including a movable follower to engage said master pattern, and a cutter arranged co-axially with said follower to engage another 80 of said disks and to shape the same in correspondence with said master pattern.

26. The combination with a pattern generating machine having a lever provided with a pattern generator, of mechanism for 95 marking said patterns; said mechanism comprising a housing on said lever; a hammer mounted pivotally in said housing and having a resilient shank provided with a marking point, a heel provided with a latch, 100 and an operating extension; a rotatable trigger having means acting upon rotation of said trigger to engage said latch to cock said hammer and acting upon further rotation of said trigger to trip said latch; a 105 spring operating upon one side of said extension to rotate said hammer upon its pivot to impart marking motion to said shank; an adjustable stop to be engaged by the other side of said extension to limit the 110 marking stroke of said hammer at a point which will permit the impetus of said marker to bend said shank and allow marking engagement of said marker with the article to be marked, the resiliency of said 115 shank withdrawing said marker to a normal position of rest out of engagement with said article and permitting free movement of the latter; and a manually operated lever such as a foot lever to actuate said trigger. 120

27. In a machine of the class described; a pattern-blank-support; means to operate upon said pattern-blank; means to be engaged movably and concurrently with a plurality of differently curved regions of the 125 model; and means to impart to said support and operating means a relative movement resultant from, and corresponding to, the relative movements of said model-engaging means.

28. In a machine of the class described; means to be engaged movably and concurrently with a plurality of differently shaped regions of a model; and means to impart to 5 a pattern of different general shape from said model a contour embodying the relative variations in contour of said engaged model regions, to render said pattern capable of service in the production of shapes 10 having such relative variations.
29. In a machine of the class described; means to be engaged movably and concurrently with a plurality of differently shaped regions of a model; and means controlled by 15 said model-engaging means to impart to the periphery of a disk a contour embodying the relative variations in contour of said engaged model regions.
30. In a machine of the class described; 20 mechanism for producing, in a pattern of dissimilar general shape from the model, variations of contour capable of serving as pattern surfaces in the reproduction of shapes similar to said model; said mechanism comprising means arranged and adapt- 25

ed for concurrent movable engagement with said model at a plurality of regions of said model differing in contour and parallel with the direction of relative movement between said model and means; said regions of engagement lying upon the same side of said model and in substantially the same transverse plane, relatively to the direction of relative movement between said model and model-engaging means; a pattern-blank support; means to operate upon said blank; and connecting means between said model-engaging means and said operating means to permit the latter to produce upon said blank a pattern surface embodying the relative variations between the model portions respectively engaged. 30 35 40

In testimony whereof I have signed my name to this specification in the presence of two subscribing witnesses.

FREDERICK HENRY PERRY.

ARTHUR L. RUSSELL.

Copies of this patent may be obtained for five cents each, by addressing the "Commissioner of Patents,
Washington, D. C."

It is hereby certified that in Letters Patent No. 1,027,562, granted May 28, 1912, upon the application of Frederick Henry Perry, of Beverly, Massachusetts, for an improvement in "Pattern-Generating Apparatus," errors appear in the printed specification requiring correction as follows: Page 7, line 7, for the word "lines" read *planes*, and same page, line 127, strike out the word "adjustable"; and that the said Letters Patent should be read with these corrections therein that the same may conform to the record of the case in the Patent Office.

Signed and sealed this 16th day of July, A. D., 1912.

[SEAL.]

C. C. BILLINGS,
Acting Commissioner of Patents.
